UNITED STATES PATENT OFFICE.

JAMES F. THAYER, OF PROVIDENCE, RHODE ISLAND.

STAPLE-FASTENER.

SPECIFICATION forming part of Letters Patent No. 427,280, dated May 6, 1890.

Application filed March 19, 1890. Serial No. 344,568. (No model.)

To all whom it may concern:

Be it known that I, JAMES F. THAYER, a citizen of the United States, residing at Providence, in the county of Providence and State 5 of Rhode Island, have invented certain new and useful Improvements in Staple-Fasteners; and I do declare the following to be a full, clear, and exact description of the invention, such as will enable others skilled in the 10 art to which it appertains to make and use the same, reference being had to the accompanying drawings, and to the letters of reference marked thereon, which form a part of this specification.

15 My present invention relates to an improvement in metallic button-fasteners; and it consists, essentially, of a two-pronged wire staple having a crown or arch and legs of a uniform size, and notched or cut away at or near the 20 point of intersection of the crown and legs, and having enlarged or expanded free ends, all as will be hereinafter more fully described.

Figure 1 represents a plan view of my improved staple-fastener. Fig. 2 is a side elevation of the same. Fig. 3 represents the 25 fastener with button as secured to fabric.

Referring to the drawings, A represents my improved fastener, formed in the present instance of round wire and of inverted-U shape, 30 comprising the crown or arch a and legs c c, terminating in enlarged or expanded free ends d d, said ends being outwardly beveled and thinned at the points, the cutting-edges of the same standing at right angles to the 35 length of the staple, as shown in Figs. 1 and 2 of the drawings, the legs above the expanded ends and the crown of the staple being of a uniform size. The outer sides of the staple A are notched or cut away, as at b, at or near 40 the point of intersection of the crown and legs to prevent the staple from tipping sidewise

in the jaw of a setting-instrument while being secured to fabric, as shown in the drawings.

When secured to fabric with a button, the 45 legs of the staple after passing through the fabric are bent outward and clinched on the under surface of the same, as illustrated in Fig. 3, the notches b b being substantially on a line with the upper surface of the fabric.

The advantages of my improvement are 50 evident without a more minute detail. Any desired form of wire may be employed, and the crown or arch of the staple may be varied in shape. As previously stated, the notches form bearing-surfaces on opposite sides of 55 the staple to prevent it from tipping sidewise in the setting-instrument, and by weakening the legs of the fastener somewhat forms a determinate bend at that point, thus materially assisting in the clinching operation, as 60 in attachment to fabric. A reliable staple-button fastener is thus produced at a small cost for manufacture.

Having described my invention, I claim—

1. A staple-fastener comprising a crown 65 and legs composed of metal of uniform size and notched or cut away at or near the point of intersection of the crown and legs and having outwardly beveled and enlarged or expanded free ends, substantially as herein 70 specified.

2. A staple-fastener made from wire, having a crown and legs and notched or cut away at or near the point of intersection of the crown and legs, substantially as and for the 75 purpose set forth.

In testimony whereof I affix my signature in the presence of two witnesses.

JAMES F. THAYER.
